(57) **CLAIM**

The ornamental design for a firearm rail, as shown and described.

DESCRIPTION

FIG. 1 is a bottom, rear, left side perspective view of a firearm rail according to the present disclosure;

FIG. 2 is a front view of the firearm rail of FIG. 1;

FIG. 3 is a rear view of the firearm rail of FIG. 1;

FIG. 4 is a right side view of the firearm rail of FIG. 1;

FIG. 5 is a left side view of the firearm rail of FIG. 1; and,

FIG. 6 is a bottom view of the firearm rail of FIG. 1.

The broken lines depict portions of the firearm rail that form no part of the claimed design. Broken line features and surfaces adjacent to claimed areas defined by shading form no part of the claimed design.

1 Claim, 4 Drawing Sheets(56)
